YARN TENSION DEVICE

William T. Stearn, Cumberland, Md., assignor to
 Celanese Corporation of America, New York,
 N. Y., a corporation of Delaware

Application May 2, 1950, Serial No. 159,581

12 Claims. (Cl. 242—45)

1

This invention relates to yarn tension devices and relates more particularly to adjustable yarn tension devices and to textile equipment in connection with which said adjustable yarn tension devices are employed.

In textile operations wherein yarn is drawn from one point to another, such as in the winding of yarn from a supply to a take-up package, it is necessary to apply tension to the yarn during the winding operation. It has previously been proposed to apply tension to the yarn by devices of various types such as discs, whorls, gates and springs. Some of these types of tension devices are suitable for particular operations, but are unsuitable for others. Few are consistently satisfactory where adjustments are necessary during the winding operation.

For example, in cone winding the yarn is drawn vertically from a supply package and, after passing through some form of yarn tension device, is traversed by a reciprocating guide onto a cone tube. The cone tube is mounted on a mandrel driven at a constant speed so that as the yarn builds up on the cone tube the rate of yarn take-up increases. This change in the rate of yarn take-up tends to increase the yarn tension and some adjustment must be made in the yarn tension apparatus if the yarn tension is to be reduced during the entire winding operation, which reduction in tension is necessary to obtain a satisfactory cone. When the adjustments in the yarn tension devices must be made manually, the yarn tension is liable to considerable variation owing to faulty adjustments and to the relative infrequency with which the necessary adjustments are made. The variations in yarn tension often lead to the production of defective cones.

It is an important object of this invention to provide a yarn tension device which will be free from the foregoing and other disadvantages of yarn tension devices previously employed and which will be especially simple in construction and efficient in use.

A further object of this invention is to provide a readily adjustable yarn tension device.

Another object of this invention is the provision, in a textile apparatus wherein yarn is drawn from one point to another, of a yarn tension device that is automatically adjusted during operation.

Other objects of this invention, together with certain details of construction and combinations of parts, will be apparent from the following detailed description and claims.

2

According to the present invention, there is provided a yarn tension device comprising a generally elongated friction surface, and means positioned at points spaced longitudinally of the friction surface for guiding the yarn generally longitudinally thereof and for bringing the yarn into contact therewith, said means being adjustable with respect to each other so as to vary the extent of contact between the yarn and the friction surface thereby to adjust the yarn tension. The friction surface may advantageously have a generally circular cross-section and comprise a pair of tubes aligned one with the other. Yarn guide means may be positioned at points spaced axially of the tubes for guiding the yarn generally parallel to the axis of the tubes, and additional, adjustable yarn guide means may be positioned intermediate said aforementioned yarn guide means so as adjustably to wrap the yarn around the tubes, thereby to adjust the yarn tension readily over a wide range. The regulation of the yarn tension may be effected automatically by linking the adjustable yarn guide means to the textile equipment in which it is employed. For example, in a yarn-winding machine, the wrap of the yarn around the tubes may be decreased automatically in proportion to the increase in the yarn take-up rate so as to reduce the tension on the yarn during the winding operation.

A preferred embodiment of the yarn tension device of this invention as applied to a coning machine is shown in the accompanying drawings wherein

Fig. 1 is a side elevational view of the yarn tension device and a portion of the coning machine to which it is applied,

Fig. 2 is a cross-sectional view taken along the line 2—2 in Fig. 1 in the direction of the arrows, and

Fig. 3 is a cross-sectional view, on an enlarged scale, taken along the line 3—3 in Fig. 1 in the direction of the arrows.

Referring now to the drawings, the reference numeral 11 designates a yarn which is drawn from a supply (not shown) and, after passing through a yarn tension device indicated generally by reference numeral 12, is directed by a reciprocating guide 13, which may be constructed in the manner shown in my co-pending application S. No. 107,053, filed July 27, 1949, onto a cone 14 in a manner well known in the art. The reciprocating guide 13 is carried at the upper end by an arm 15 that is pivotally mounted on machine frame 16 by means of a shaft 17. Fastened

to the lower end of the arm 15 is a counterweight 18 that urges the reciprocating guide 13 into contact with the surface of the cone 14. As the yarn builds up on the cone 14, it causes the reciprocating guide 13, the arm 15 and the counterweight 18 to rotate about the shaft 17 in a clockwise direction (Fig. 1).

The yarn tension device 12 comprises two chromium-plated stainless steel tubes 19 and 21 that are aligned one with the other. A brass plug 22 having an annular ring 23 projecting therefrom is press-fitted into the lower end of the tube 19, and a similar brass plug 24 having an annular ring 25 projecting therefrom is press-fitted into the upper end of the tube 21. In the center, the two tubes 19 and 21 are separated one from the other by means of a brass plug 26 that has bosses 27 and 28 projecting into the tubes 19 and 21 and is freely rotatable with respect to said tubes. Yarn guides, such as pigtailed 29, 31 and 32, through which the yarn 11 passes, are fastened to the plugs 22, 24 and 26, the pigtailed 29 and 31 being aligned one with the other.

The plug 26 is secured to a shaft 33 extending lengthwise of the tubes 19 and 21 and mounted for free rotation with respect to the plugs 22 and 24 in ball bearings 34 and 35 positioned internally of the annular rings 23 and 25. The upper end of the shaft 33 extends through the plug 24 and has fastened thereto a bevel gear 36 that meshes with a segmental bevel gear 37 mounted for free rotation on a stud 38. The bevel gear 37 is linked to the counterweight 18 by means of a rod 39. One end of the rod 39 extends through an angle bracket 41 welded or otherwise fastened to the counterweight 18, and is held in place by collars 42 positioned on both sides of said bracket. The other end of the rod 39 extends through the bevel gear 37 at a point above the stud 38, and is held in place by collars 43, positioned on both sides of said bevel gear. The yarn tension device 12 is mounted on a U-shaped support 44, the stud 38 extending through said support, the plug 22 being fastened to said support by means of a bolt 45 in threaded engagement therewith, and the plug 24 being fastened to said support by means of a stud 46 in threaded engagement therewith. The U-shaped support 44 is attached to the machine frame 16 by means of a bracket 47.

In operation, when the winding of the yarn 11 onto a cone 14 is to begin, the arm 15 is rotated in a clockwise direction (Fig. 1) to move the reciprocating guide 13 clear of the cone 14 and permit a new cone tube to be placed in position. As the arm 15 rotates in a clockwise direction, the rod 39 fastened thereto will cause the bevel gear 37 to rotate in a counterclockwise direction (Fig. 1) about the stud 38, driving the bevel gear 36 in a clockwise direction (Fig. 2). The clockwise rotation of the bevel gear 36 will cause the shaft 33 and the plug 26 fastened thereto to rotate in the same direction, moving the pigtail 32 in a clockwise direction as shown by the arrow in Fig. 2. The linkage between the counterweight 18 and the bevel gear 37 and the ratio of the bevel gear 36 to the bevel gear 37 is so designed that when the arm 15 is moved to the starting position, the pigtail guide 32 will be aligned with the pigtailed 29 and 31, permitting the yarn 11 to be threaded readily through said pigtailed and through the reciprocating guide 13 for fastening to the cone 14. The arm 15 is then permitted to rotate in a counterclockwise direction (Fig. 1) until the reciprocating guide 13 bears against the cone 14. The counterclockwise rotation of

the arm 15 will cause the bevel gear 37 to rotate in a clockwise direction (Fig. 1), driving the bevel gear 36, the plug 26 and the pigtail 32 in a counterclockwise direction (Fig. 2), wrapping the yarn 11 around the tubes 19 and 21 as shown in Fig. 1.

The winding of the yarn 11 onto the cone 14 may then be started, the tension on the yarn 11 being determined by the frictional forces between said yarn and the tubes 19 and 21. The frictional forces may be adjusted for tubes 19 and 21 of a given length and diameter, by varying the wrap of the yarn 11 around said tubes either by changing the mechanical advantage of the linkage between the arm 15 and the bevel gear 37, or by altering the ratio between the bevel gears 36 and 37 or by a combination of these expedients. As the yarn 11 builds up on the cone 14, which is driven at a constant speed, the rate of yarn take-up will increase, which increase will tend to raise the yarn tension. Simultaneously, however, the yarn 11 wound on the cone 14 will cause the reciprocating guide 13, the arm 15 and the counterweight 18 to rotate in a clockwise direction (Fig. 1). The clockwise rotation of the counterweight 18 will move the rod 39 to the left (Fig. 1) and cause the bevel gear 37 to rotate in a counterclockwise direction (Fig. 1), driving the bevel gear 35, the shaft 33, the plug 26 and the pigtail 32 in a clockwise direction (Fig. 2), thereby decreasing the wrap of the yarn 11 around the tubes 19 and 21 and tending to reduce the yarn tension. With proper design, the reduction in yarn tension caused by the decreased wrap of the yarn 11 around the tubes 19 and 21 will more than balance the increased yarn tension caused by the increased take-up rate of said yarn so that the yarn tension will be gradually reduced during the winding operation.

The yarn tension device of this invention has a considerable number of advantages over the devices previously used for this purpose. It is positive acting and may be adjusted readily over an extremely wide range. It may be used successfully to wind yarn of extremely high twist without kinking, and also to wind yarns of extremely low twist without stripping fibers or filaments from the yarns. It reduces end breakage and improves yarn quality by eliminating the possibility of strained yarns. It obviates underwinding the cones and bulged cones caused by tension variations and permits of better density control thereby producing more uniformly wound cones even when the cones are wound with a high traverse. It also eliminates crushed cone tubes and permits of the use of lighter cone tubes effecting an important saving in costs. As compared with gates, the yarn tension device of this invention has a lower threading time, permits of higher winding speeds, and less frequent cleanings, and produces fewer stoppages as the result of vibration. In addition, because the area of contact between the yarn and the friction surface changes continuously during operation, wear of the friction surfaces against which the yarn bears occurs less rapidly.

While the yarn tension device of this invention has been described as having two tubes over which the yarn is drawn, it may be constructed with only a single tube although this form of construction is somewhat less desirable.

It is to be understood that the foregoing detailed description is given merely by way of illustration and that many variations may be made therein without departing from the spirit of my invention.

Having described my invention, what I desire to secure by Letters Patent is:

1. A yarn tension device comprising a generally elongated friction surface, means positioned at points spaced longitudinally of the friction surface for guiding the yarn generally longitudinally of the friction surface, and means positioned intermediate said aforementioned means for bringing the yarn into free contact with the friction surface, said latter means being angularly adjustable to vary the extent of free contact between the yarn and the friction surface thereby to adjust the yarn tension.

2. A yarn tension device comprising a pair of generally elongated friction surfaces aligned one with the other, means positioned at points spaced longitudinally of the friction surfaces for guiding a yarn generally longitudinally of the friction surfaces, and means positioned intermediate said friction surfaces for bringing the yarn into free contact with the friction surfaces, said latter means being angularly adjustable to vary the extent of free contact between the yarn and the friction surfaces thereby to adjust the yarn tension.

3. A yarn tension device comprising a friction surface having a generally circular cross-section, means positioned at points spaced axially of the friction surface for guiding a yarn generally parallel to the axis of the friction surface, and means positioned intermediate said aforementioned means for bringing the yarn into contact with the friction surface, said latter means being angularly adjustable to vary the extent of contact between the yarn and the friction surface thereby to adjust the yarn tension.

4. A yarn tension device comprising a pair of friction surfaces having a generally circular cross-section aligned one with the other, means positioned at points spaced axially of the friction surfaces for guiding a yarn generally parallel to the axis of the friction surfaces, and means positioned intermediate said friction surfaces for bringing the yarn into contact with the friction surfaces, said latter means being adjustable to vary the extent of contact between the yarn and the friction surfaces thereby to adjust the yarn tension.

5. A yarn tension device comprising a pair of tubes aligned one with the other, yarn guide means positioned adjacent the ends of the tubes that are spaced furthest from each other for guiding a yarn generally parallel to the axis of the tubes, and a yarn guide means positioned intermediate the tubes for bringing the yarn into contact with the surface of the tubes, said latter yarn guide means being adjustable to vary the extent of contact between the yarn and the tubes thereby to adjust the yarn tension.

6. A yarn tension device comprising a pair of tubes aligned one with the other, yarn guide means positioned adjacent the ends of the tubes that are spaced furthest from each other for guiding the yarn generally parallel to the axis of the tubes, a yarn guide means positioned intermediate the tubes for bringing the yarn into contact with the surface of the tubes, and a shaft extending axially of at least one of the tubes for adjusting said latter yarn guide means to vary the extent of contact between the yarn and the tubes thereby to adjust the yarn tension.

7. A yarn tension device comprising a pair of tubes aligned one with the other, yarn guide means fixedly positioned adjacent the ends of

the tubes that are spaced furthest from each other for guiding a yarn generally parallel to the axis of the tubes, and a yarn guide means positioned intermediate the tubes for bringing the yarn into contact with the surface of the tubes, said latter yarn guide means being rotatable with respect to the tubes to vary the extent of contact between the yarn and the tubes thereby to adjust the yarn tension.

8. A yarn tension device comprising a pair of tubes aligned one with the other, yarn guide means fixedly positioned adjacent the ends of the tubes that are spaced furthest from each other for guiding a yarn generally parallel to the axis of the tubes, a yarn guide means positioned intermediate the tubes for bringing the yarn into contact with the surface of the tubes, and means for rotating said latter yarn guide means with respect to the tubes to vary the extent of contact between the yarn and the tubes thereby to adjust the yarn tension.

9. A yarn tension device comprising a pair of tubes aligned one with the other, plugs fixedly positioned in the ends of the tubes that are spaced furthest from each other, yarn guide means fastened to said plugs for guiding a yarn generally parallel to the axis of the tubes, a plug positioned intermediate the tubes and rotatable with respect thereto, yarn guide means fastened to said latter plug for bringing the yarn into contact with the surface of the tubes, and a shaft extending axially of the tubes and fixed to said latter plug for rotating said plug and the yarn guide means fixed thereto to vary the extent of contact between the yarn and the tubes thereby to adjust the yarn tension.

10. In a yarn winding apparatus wherein yarn is drawn from a supply and wound on a take-up package driven at a constant rotational speed so that the rate of yarn take-up increases as the yarn builds up on the take-up package, a yarn tension device comprising a pair of generally elongated friction surfaces aligned one with the other, yarn guide means positioned at points spaced longitudinally of the friction surfaces for guiding a yarn generally longitudinally of the friction surfaces, yarn guide means positioned intermediate said friction surfaces for bringing the yarn into free contact with the friction surfaces before it is wound on the take-up package, and means operated by the yarn on the take-up package for adjusting said latter yarn guide means angularly to reduce the extent of free contact between the yarn and the friction surfaces as the yarn builds up on the take-up package and the rate of yarn take-up increases thereby to adjust the tension on the yarn during the winding operation.

11. In a yarn winding apparatus wherein yarn is drawn from a supply and wound on a take-up package driven at a constant rotational speed so that the rate of yarn take-up increases as the yarn builds up on the take-up package, a yarn tension device comprising a pair of friction surfaces having a generally circular cross-section aligned one with the other, yarn guide means positioned at points spaced axially of the friction surfaces for guiding a yarn generally parallel to the axis of the friction surfaces, yarn guide means positioned intermediate said friction surfaces for bringing the yarn into contact with the friction surfaces before it is wound on the take-up package, and means operated by the yarn on the take-up package for adjusting said latter yarn guide means to reduce the extent of contact between the yarn and the friction surfaces.

faces as the yarn builds up on the take-up package and the rate of yarn take-up increases thereby to adjust the tension on the yarn during the winding operation.

12. In a yarn winding apparatus wherein yarn is drawn from a supply and wound on a take-up package driven at a constant rotational speed so that the rate of yarn take-up increases as the yarn builds up on the take-up package, and the yarn is guided onto the take-up package by means bearing against the take-up package and mounted on a pivotally supported arm, a yarn tension device comprising a pair of tubes aligned one with the other, plugs fixedly positioned in the ends of the tubes that are spaced furthest from each other, yarn guide means fixed to said plugs for guiding a yarn generally parallel to the axis of the tubes, a plug positioned intermediate the tubes and rotatable with respect thereto, yarn guide means fixed to said latter plug for bringing the yarn into contact with the surface of the tubes before it is wound on the take-up package, a shaft extending axially of tubes and fixed to said latter plug for rotating said

latter plug and the yarn guide means fixed thereto, and means including a link fastened to said pivotally supported arm and a pair of gears fastened to said link and to said shaft for rotating said shaft to reduce the extent of contact between the yarn and the tubes as the yarn builds up on the take-up package and the rate of yarn take-up increases thereby to adjust the tension on the yarn during the winding operation.
